METAL PARTITION SCRIBER

John A. Bohnsack, Cleveland Heights, and
 Edward Heller, Cleveland, Ohio, assignors to
 The E. F. Hauserman Company, Cleveland,
 Ohio, a corporation of Ohio

Application July 9, 1929, Serial No. 377,050

14 Claims. (Cl. 189—34)

This invention relates to metallic partitions, and more particularly construction where joining against old surfaces; and it is among the objects of the invention to provide a construction adaptable to various conditions of walls and ceilings encountered. A further object is the provision of a construction which can be taken down and be readily reerected in the event of necessity for removal. Other objects and advantages will appear as the description proceeds.

To the accomplishment of the foregoing and related ends, the invention, then, consists of the features hereinafter fully described, and particularly pointed out in the claims, the following description and the annexed drawing setting forth in detail certain structure embodying the invention, such being illustrative however, of but a few of the various ways in which the principle of the invention may be employed.

20 In said annexed drawing:

Fig. 1 is an elevation showing a portion of a partition in accordance with the invention, the surrounding structure being in section; Figs. 2, 3 and 4 are detail sections taken respectively on planes indicated by the lines II—II, III—III and IV—IV, Fig. 1; Fig. 5 is a perspective view of a detached clip; and Fig. 6 is a fragmentary detail of a flange of the vertical member.

Referring more particularly to the drawing, 30 there is shown a partition comprising panel units *b*, *b* assembled with a cornice *c* and a vertical support member *v*. Between such structure and the adjacent wall to be connected to is a section comprising members *a* extending to engage in a wall 35 connector, as a wall channel *e*. The latter, in the form of a mold having rebent flanged edges, is adapted to engage against the wall, which in old construction encountered is usually of a plaster finish, and to further facilitate good engagement 40 therewith, the web of such channel or mold may have extrusions or semipunchings *m* such as to embed and primarily provide against shifting. Within the channel member is an internal spacer 45 *j*, which may be of wood or hollow metal and may be continuous or in the form of blocks spaced at intervals. In its preferred form, such spacer stands out beyond the flanges of the channel, and is of a cross section narrower against the web and widened at its outer portion. It may be placed in 50 position and fastened directly to the wall by suitable plane or expanding fastenings, or in some instances it is sufficient to provide a wedge across from an adjacent vertical member for instance by a thrust wedge or strut *p* (Fig. 1).

55 The support members *v* comprise in general a

framing vertical member *i* of generally channel shape and having a groove in its web for the reception of the panel stretcher. The flanges *i'* of such vertical member are provided with longitudinal slots *i*² adapted to receive tongues *t* of a 60 clip *k*. The latter is of generally channeled form having flanges or wings *k'* and a connecting web or body *w*. Such clips are of stamped sheet metal of suitable gauge, and at the juncture between wings and web are bent in an easy curve, and 65 this together with the cutout or narrowed web portion *w*, allows of a slight springing or forcing of the wings *k'*, sufficient yielding being had that the wings may be spread to allow the tongues *t* to slip over the flanges and into the slots *i*² and interlock therewith. A beading or reinforce *k*² may 70 be incorporated in the wings in the stamping, to further strengthen the structure without necessarily undue weight.

The panel unit *b* with end vertical member *i* is 75 set in position, and the cornice member *c* placed above it and extending to the wall. The clips *k* may now be brought into assembly with the vertical member *i*, the wings of the clips being spread sufficiently to allow the tongue *t* to slide over the 80 flanges *i'* and seat into the slots *i*², interlocking therewith. The scribe sheets *a* in their preferred form are provided with an offset, and afford a finish molding having a flange *a'* further rebent towards and parallel to the body of a sheet. With 85 such construction, the plane edge of the scribe may be inserted between the flange of the channel mold *e* and the spacer block *j*, the scribe plate for such positioning being swung around angularly with respect to the plane of the partition, as indicated in dotted lines in Fig. 4. On 90 now swinging the plate inwardly, the edge of the spacer *j* acting as a fulcrum, the molding margin of the scribe is brought against the vertical member *i*. At the same time that the plate *a* is swung 95 into its final position, its upper edge, preferably provided with an offset *o*, Fig. 2, is inserted into the recess of the cornice, being lifted as necessary, so as to snugly engage therewith. By a sharp blow the flange *a'* is snapped over and behind locking 100 projections *k*³ on the clip. The final appearance is thus that of a finished post with a stretcher extending therefrom to the wall.

For a neat and consistent effect at the floor-engaging portion of the scribe element, a mold *f* 105 is desirably employed, and in its preferred construction, this may be made up of two generally angle-shaped sheet metal members nested together such that two flanges, as at *f'* may be welded or otherwise fastened together, while the 110

other flanges are slightly spaced apart, the outer angle member having its upstanding flange further rebent as at f^2 to present a finished appearance, and the inner flange f^3 may extend higher, in order to permit easy initial assembly of the mold with the scribe sheet. It will be understood that this is accomplished before the scribe sheet is swung around into its final position, and by reason of the telescopic engagement of the 10 mold with the scribe or plate a , final adjustment down snugly with the floor may be readily had.

Plinths g may be attached to the verticals below, finishing the joint at the floor and making a neat contact therewith.

15 In a similar manner, scribe sections may be connected between a partition and the ceiling as required. Obviously also, the details as described in their preferred form may be varied, as for instance the notching in the clip may be changed, 20 or the notches may be shaped to support the brace wedge; again, the offset in the top of the sheets may be omitted or the contour of the cornice may be varied, and the floor mold may be varied in shape or be omitted entirely. The wall 25 mold may be varied to such an extent that the sheets may be fastened directly to the internal spacer, and the clips may be clamped or otherwise applied to the verticals or be made in more than one part.

30 And in general, other modes of applying the principle of the invention may be employed, change being made as regards the details disclosed, provided the means stated in any of the following claims, or the equivalent of such, be employed.

35 We therefore particularly point out and distinctly claim as our invention:—

1. In partition construction, a support having 40 extending flanges, attaching means including a clip having faces in different planes and having means providing resilient flexure on lines localized between the faces of the clip to permit engagement with the vertical without deforming the faces, and means on said clip for receiving a finish member.

45 2. In partition construction, a support having flanges with slots therein, and attaching means including a clip having faces in different planes to mate with the flanges of said vertical, said clip 50 having hook tongues engageable in said slots and having means permitting flexure selectively between clip-faces to permit insertion or removal of the tongues from the slots.

3. In partition construction, a support having 55 flanges and attaching means including a clip having faces in different planes to mate with the flanges of the vertical, said clip having means providing resilient flexure between the clip faces to permit engagement with the vertical without deforming the faces, locking projections on the 60 free ends of the clip wings, and means on said clip for receiving a finish member.

4. In partition construction, a support having 65 extending flanges, and attaching means including a clip having faces in different planes to mate with the flanges of the vertical, said clip having wings and a connecting web portion with junctions in easy curves and being capable of flexure, the free ends of such wings being provided with 70 tongues and locking projections.

5. In partition construction, a combined scribe 75 sheet and vertical support facing having a molding at one margin, said molding comprising an offset and a rebent securing flange engageable over locking projections, and means for main-

taining said scribe sheet between a vertical support and a wall.

6. In partition construction, a scribe sheet having a molding at one margin, said molding comprising an offset and a bent flange further 80 rebent towards and parallel to the sheet, and a clip retaining said sheet between a vertical support and a wall by resilient contact by said offset and rebent flange.

7. In partition construction, a sheet metal wall 85 or ceiling mold of generally channel shape, the web portion adapted to lie against a wall or ceiling, a partition member engageable therein, and an internal spacing strip extending in said channel and providing a longitudinal lever-edge at 90 each side, and being thence under-cut toward the web of the channel.

8. In partition construction, a sheet metal wall or ceiling mold of generally channel shape, the web portion adapted to lie against a wall or ceiling, and an internal spacer extending beyond the flanges of said channel and lying against its web, 95 said spacer being narrower at the web-engaging portion than at its outstanding portion, and a filler sheet insertable angularly to the web and 100 adapted to be held by said spacer when swung normal to the web of said channel.

9. In partition construction, a sheet metal wall or ceiling mold of generally channel shape, the web portion adapted to lie against a wall or ceiling, 105 and an internal spacer extending beyond the flanges of said channel and lying against its web, said spacer being narrower at the web-engaging portion than at its outstanding portion, and a filler sheet insertable angularly to the web and 110 clamped between said channel and said spacer when swung normal to the web of said channel.

10. In partition construction, a sheet metal wall mold of generally channel shape, the web portion adapted to lie against a wall, an internal spacer 115 extending beyond the flanges of said channel and lying against its web, said spacer being narrower at the web engaging portion than at the outstanding portion, a vertical support spaced from the wall, a filler sheet insertable angularly to the web 120 of said wall mold, and interlocking means on said vertical support for holding said filler when turned normal to the wall.

11. In partition construction, a sheet metal wall mold of generally channel shape, the web portion 125 adapted to lie against a wall, a vertical flange support member, a clip having faces in three planes and engaging the flanges of said vertical, a filler sheet insertable in the web of the wall channel and having on its other margin a molding 130 comprising an offset and a bent flange further rebent towards and parallel to the sheet, and means for locking said filler sheet when turned normal to the wall, said means including said rebent flange on the molding margin and a locking 135 projection on said clip engageable by said rebent flange.

12. In partition construction, means for receiving spaced edges of metallic partition members and forming an adjustable abutment finish, 140 said means comprising angular pieces nested with one pair of flanges joined and the other pair slightly spaced, one member of the latter being rebent as a finish on the outside of the partition member.

13. In partition construction, means forming an adjustable abutment finish, said means comprising angular pieces nested with one pair of flanges joined and the other pair slightly spaced, 145 the outer of said flanges being rebent toward the 150

other, and the inner of said flanges extending higher than the outer.

14. In partition construction, a support having extending flanges, and attaching means including a clip of generally channel shape, having its

web portion narrowed by cutouts, and the free ends of the flanges having tongues and locking projections.
